UNITED STATES PATENT OFFICE.

JOHN F. ROBB, OF CLEVELAND HEIGHTS, OHIO, ASSIGNOR, BY MESNE ASSIGNMENTS, TO KOEHRING COMPANY, OF MILWAUKEE, WISCONSIN, A CORPORATION OF WISCONSIN.

APPARATUS FOR LAYING REINFORCED CONCRETE.

Application filed March 26, 1921. Serial No. 455,887.

To all whom it may concern:

Be it known that I, JOHN F. ROBB, a citizen of the United States, residing at Cleveland Heights, in the county of Cuyahoga and State of Ohio, have invented certain new and useful Improvements in Apparatus for Laying Reinforced Concrete, of which the following is a specification.

At the present time, in the construction of concrete roads, it is customary to deposit a base layer of concrete by the use of a suitable distributing machine, thereafter lay upon the concrete a section of reinforcing, and then deposit upon the reinforcing, and then deposit upon the base layer of concrete a surface layer or section of concrete. The concrete is distributed by machinery but the metal reinforcement employed is handled manually, several laborers being required in order to transfer the reinforcement from a side of the road to its proper place upon the preliminary first or base layer of concrete above referred to.

In view of the fact that specifications for road building contracts are more and more requiring the use of reinforcement to afford the utmost precaution and safety against longitudinal breaking of the road when built, the need of efficient means of laying the concrete with the reinforcement, avoiding the laborious handling of the latter, will be self evident.

The object of this invention has been to design a compact machine, and devise an efficient means, whereby to lay concrete roads with reinforcement imbedded therein in a single progressive operation. In other words, the concrete and reinforcement are simultaneously deposited, and separate operations of depositing the concrete into distinct layers, and handling the reinforcement at a time intermediate said depositing operations, are avoided.

In the accompanying drawings—

Figure 1 illustrates one embodiment comprising a machine by which the invention hereinafter set forth may be carried out;

Figure 2 is a diagrammatic view showing a slightly different relative arrangement of the mixer, a somewhat different form of distributor, and a different way of supporting the machine over the subgrade.

At A in the drawings is illustrated a conventional type of concrete mixer having a

tiltable discharge and mixing chute B. The chute B is adapted to conduct mixed concrete to the distributing chute C which leads to the subgrade 1 of the road. The mixer is adapted to be supplied with large quantities of aggregates to be mixed therein, by means of a derrick comprising a mast 2 and boom 5, with suitable equipment by which the boom may be connected to hoist boxes or car-bodies 3 filled with said aggregates and adapted to be discharged into a hopper 4 leading to the charging end of the mixer A.

The mixing and distributing plant thus far described, also loading derrick, are mounted upon a suitable support adapted to be propelled by any suitable means, a gas motor or a steam engine being often used. The portable support just referred to is designated 6 and may comprise wheels 7 by which it is adapted to travel upon the road forms 8, at opposite sides of the road, said forms constituting rails. At a point adjacent to the derrick which is generally indicated at D, the support 6 is provided with standards 6^a to carry the shaft 9 on which is mounted a bale or reel of reinforcement, such as bar mesh, or metal fabric used in reinforcing concrete roads. From the bale of reinforcement designated 10 the said reinforcement is adapted to be fed between straightening rolls 11 to guide rolls 12 which are carried by depending arms 13 adjustably supported at 14 upon the support or truck 6. By anchoring the free end of the reinforcement 10 preliminarily to the use of the machine, it will be evident that as the machine progresses over the subgrade of the road the reinforcing 10 unwinds from the bale formation thereof, is straightened, and guided and held in proper position over the subgrade.

At the same time as the machine is propelled forward the mixed concrete aggregates are discharged upon the subgrade by the chutes B and C. The aggregates pass thru the reinforcement material which is of large mesh and in no way offers an obstacle to such operation.

From the foregoing it will be evident that in a progressive continuous manner concrete and reinforcing may be laid upon the subgrade of the road, the reinforcing being imbedded at the proper depth adapted to be

regulated as required, and the distinct and separate operations heretofore performed in actual practice are combined in a single operation with resultant advantage.

5 The derrick D used to load the mixer A is also useful for the purpose of loading bales of reenforcing fabric or metal into position upon the standards 6^a. For this purpose simple grapple equipment intermediate 10 the derrick and shaft 9 is employed.

Figure 2 shows a machine similar to that above described in all general principles. The main differences of construction are the employment of endless tracks or caterpillars 15 at 15 to carry the main weight or load of the machine and materials supported thereon, and adapted to travel on the subgrade itself. The distributor C' is a boom and bucket type 20 of distributor, well known in the art. The rear end of the support or truck is extended as shown at 16 so that the arms 13 and guide rolls 12 may be properly positioned to hold the reenforcing material at a correct 25 elevation as the bucket distributor deposits the aggregates in position upon the sub-grade.

Of course when the road is once started in construction the aggregates which have been laid form a means for firmly holding the 30 fabric, as soon as these aggregates begin to set.

If desired, the reenforcing material may be positively fed from the machine by pulling devices and for this purpose the rear-most of the feeding and guiding rollers 12 may be positively driven from the motor of the machine.

Having thus described my invention, what 40 I claim as new and desire to obtain by Letters Patent is:

1. In a machine for constructing concrete roads, in combination, a portable support adapted to travel over a road subgrade, a concrete distributing unit mounted upon 45 said support, and adapted to feed concrete aggregates to the subgrade, concrete reenforcing supply means on said portable support, and means carried by said support for supporting said reenforcing in spaced relation from the concrete distributor and in spaced relation to the base of the subgrade,

so that materials fed from the concrete distributor pass through the reenforcing to a predetermined depth below the same, and cover said reenforcing to a predetermined 55 depth above the same.

2. In a machine for constructing concrete roads, in combination, a portable support adapted to travel over the subgrade on which the road is to be laid, concrete reenforcing 60 supply means on said support, a motor for moving the support and thereby causing a feeding of the reenforcing material from its supply means to the subgrade, means carried by said support and including a series 65 of guiding rollers arranged above the subgrade and coacting with the reenforcing, to maintain the latter in spaced relation to the bottom of the subgrade, and means for supplying concrete aggregates to the sub-grade from a point above the reenforcing feed thereon, and simultaneously with the feeding action of said reenforcing, so that the concrete passes through the reenforcing and over the same as the machine travels in 70 progressing along the road bed.

3. In a concrete road building machine, in combination, a portable support to travel over the road subgrade, concrete supply means on said support, a concrete distributor adapted to distribute materials to the sub-grade when received from said supply means, reenforcing supply means on the machine, a motor driving the portable support by progressive movement along the sub-grade so as to effect feeding of the reenforcing from the supply means, and also effect 85 a progressive distribution of the concrete aggregates as the machine advances, and supporting arms carried by said support and 90 provided with guiding means for guiding the reenforcing in its movement and maintaining its space from the base of the sub-grade, the said arms and guiding means being disposed beneath the distributor so that 95 the latter operates over the same and cause the distributed aggregates to pass through the reenforcing and above the same to a predetermined depth, thereby embedding the reenforcing therein.

In testimony whereof I affix my signature.
JOHN F. ROBB.
